[57] **CLAIM**

The ornamental design for a lavatory, as shown and described.

DESCRIPTION

FIG. 1 is a perspective view of a lavatory showing my new design;

FIG. 2 is a rear elevational view thereof;

FIG. 3 is a right side elevational view thereof, the left side view being a mirror image of the right side;

FIG. 4 is a top plan view thereof;

FIG. 5 is a bottom plan thereof; and,

FIG. 6 is a front elevational view thereof.

The broken line showing of the pedestal is for illustrative purposes only and forms no part of the claimed design.
